HEADBOARD OR THE LIKE

John J. Lubberts and Lambert J. Mulder, Grand Rapids, Mich., assignors to Tomlinson of High Point, High Point, N. C., a corporation of North Carolina

Application March 8, 1957, Serial No. 45,153

Term of patent 14 years

(Cl. D5—4)

We claim:

The ornamental design for a headboard or the like, substantially as shown.
